CLAIM

The ornamental design for a digital viewing station, as shown and described.

DESCRIPTION

FIG. 1 is a perspective view of a digital viewing station showing my new Design.

FIG. 2 is a perspective view thereof wherein the broken line showing of the x-ray illuminators and viewing monitors is for illustrative purposes only and forms no part of the claimed design;

FIG. 3 is a front elevational view thereof;

FIG. 4 is a right side elevational view thereof, the left side elevational view being a mirror image; and,

FIG. 5 is a top plan view thereof.

The rear side and the bottom of the viewing station do not form part of the design.
